UNITED STATES PATENT OFFICE.

JOHN D. AVERELL, OF NEW YORK, N. Y.

IMPROVEMENT IN CARBURETERS.

Specification forming part of Letters Patent No. 130,004, dated July 30, 1872.

To all whom it may concern:

Be it known that I, JOHN D. AVERELL, of the city, county, and State of New York, have invented an Improved Float for Carbureters; and that the following is a full, clear, and exact description of the same, reference being had to the accompanying drawing and to the letters of reference marked thereon making a part of this specification.

This invention is in the nature of an improvement in carbureters; and the invention consists in providing a float for said carbureter in such manner as will indicate when the tank of the carbureter is filled, during the process of filling the same with gasoline or other hydrocarbon.

It has heretofore been found difficult to apply to carbureters an indicator for the purpose of determining when the same is sufficiently filled with the hydrocarbon used during the process of filling the same, and thus avoid overflowing. An index-hand, with dial, has been tried; but the objection to such an appliance is, that a light of some kind is necessary to ascertain its recording, which, by reason of the highly-inflammable nature of the vapors likely to escape from the carbureter, is dangerous. Glass tubes set into the side of the carbureter are equally objectionable, from their liability to be broken, allowing the inflammable fluid and gases to escape.

To obviate these objections, and at the same time produce a sure indicator that will, without fail, indicate when the tank of the carbureter is sufficiently full, is the purpose of this invention.

In the accompanying sheet of drawing, Figure 1 is a longitudinal section of float; Fig. 2, a plan or top view of same.

Similar letters of reference indicate like parts in the several figures.

A represents a float, which is a hollow disk of metal, with an opening, B, through the center of the same. This float is carefully made fluid-tight. Secured to the under side of the float A, and extending below it, is a framework or bridge, a. Firmly secured to this bridge, by one of its ends, is a stem, b, which extends upward. Through the opening B is

inserted a cylinder, C, of somewhat less diameter than the opening B. This cylinder is open at its upper end and closed at its lower end, and the stem b passes through the axis of said cylinder, or rather through a tube, g, fitted in said cylinder. Fitting within the cylinder C is an inverted cylinder, D, which is of less diameter than the cylinder C. The lower end of the cylinder D is open, and the upper end is closed and firmly secured to the upper end of the stem b. The space between the cylinders C and D is filled with glycerine, d, or some other suitable fluid, which makes a liquid seal.

The apparatus being thus constructed, it is secured to an opening in the top plate of a carbureter by screwing the cylinder C thereto, the point of attachment being covered by a screw-cap, f. (See Fig. 1.)

The float being now in position, its operation is as follows: The necessary fluid is poured into the carbureter in the usual manner, and when the fluid has reached the height required it comes in contact with the under side of the float A and lifts it, forcing the cylinder D upward, so that it is only necessary to unscrew the screw-cap f, place the hand over the cylinder D, and when this cylinder rises sufficiently to touch the hand the carbureter is sufficiently filled. The glycerine placed in the space between the cylinders C and D effectually prevents any leakage of vapor from the carbureter through the place of attachment of the float to the carbureter.

Having thus described my invention, what I claim as new, and desire to secure by Letters Patent, is—

A float for indicating the quantity of fluid in a carbureter, when the same is constructed with a hollow disk, in combination with a cylinder having an inverted cylinder fitting therein, the space between said cylinder and said inverted cylinder being filled with a fluid for the purpose of making a liquid seal, as described.

JOHN D. AVERELL.
